UNITED STATES PATENT OFFICE

HARRY E. MENG, OF OAK PARK, ILLINOIS, ASSIGNOR TO W. D. ALLEN MANUFACTURING COMPANY, OF CHICAGO, ILLINOIS, A CORPORATION OF ILLINOIS

LAWN SPRINKLER

Application filed November 7, 1931. Serial No. 573,616.

This invention relates to lawn and garden sprinklers and more particularly such sprinklers of the flat spray type.

The object of the invention is to provide a flat spray sprinkler from which a spray of uniform length will issue from all points of the sprinkler nozzle.

Other objects and advantages of the invention will be understood by reference to the following specification and accompanying drawing, in which a flat spray nozzle embodying a selected form of the invention is illustrated.

In the drawing:—

Fig. 1 is a perspective;

Fig. 2 is a section on a plane extending through the length of the nozzle, and

Fig. 3 is a section on the line 3—3 of Fig. 2.

Referring now to the drawing, my improved nozzle includes a hollow body member 5 which includes an intake end portion 6 and a flared, fan-shaped front end or mouth portion 7. The intake end portion is provided with an enlargement 8 which is interiorly threaded, as indicated at 9, for receiving a hose connection 10 of suitable form. A rubber or other suitable washer 11 may be seated on the shoulder 12 for co-operating with the hose coupling 10 to provide a leak-proof joint between the hose coupling and the

33 sprinkler body.

The body 5 is preferably formed of cast metal, such as brass or other suitable non-rusting material, and a sheet metal spray-head 13 is mounted on the front end 7 of the body. As clearly shown in the drawing, the spray-head 13 is provided with a peripheral flange 14 which fits around the marginal front edge portion of the body and facilitates permanent connection of the spray-head and body by means of soldering or otherwise.

The sheet metal spray-head 13 is provided with a plurality of apertures 15 which permits streams of water to issue from the hollow body 5.

It has been found that, in the absence of some provision to prevent it, the streams which issue from the apertures 15 are longer near the opposite ends of the sprinkler than those which issue from the centrally located

openings. Such irregularity in the length of the streams is objectionable, and to prevent it and to cause the streams to be of uniform length throughout the length of the spray-head, I have provided a pair of metal lugs 55 16 and 17, respectively, which are cast integral with the body 5.

The lugs 16 and 17 are so shaped and arranged that they provide inside faces 18 which are substantially parallel and arranged 60 approximately in alignment with portions of the wall 6' of the inlet opening. As shown in Fig. 2, the lugs 16 and 17 are generally of triangular formation, and in addition to the substantially parallel faces 18, they provide front faces 19, which diverge outwardly and rearwardly from the spray-head 13. Rear faces 20 are also formed, these faces being approximately parallel to oppositely disposed portions 21 of the spray-head, as 70 clearly shown in Fig. 2.

The opening in the nozzle between the faces 18 of the lugs is of substantially the same cross-sectional area as the area of the inlet opening and the cross-sectional areas of the 75 spaces between the rear faces 20 of the lugs and the oppositely disposed inside face portions 21 of the body member are considerably less than the areas of the inlet opening.

I have found by actual testing of the 80 above-described structure that it serves to equalize the pressure of the water at all points on the spray-head and that the streams issuing through the apertures 15 are of substantially uniform length throughout the length 85 of the spray-head. As clearly shown in the drawing, the spray-head is of elongated, narrow proportions. As is evident from an inspection of Fig. 2, the lugs 16 and 17 serve, 90 in effect, to divide the interior of the body member into a central passageway and opposite end or side passageways or chambers.

The above described structure is susceptible of being changed in some respects without departing from the spirit of the invention, the scope of which should be determined by reference to the following claims, the same being construed as broadly as possible consistent with the state of the art.

I claim as my invention:

1. A sprinkler comprising an elongated, narrow, multi-apertured spray-head and a hollow body member to which said head is secured, the body member being provided with an inlet opening spaced rearwardly from the head and located approximately centrally of the length of the head, and means for effecting substantially uniform discharge through the openings throughout of said head, comprising a pair of substantially triangular lugs respectively on opposite sides of the path of a stream of water entering said body through said inlet openings, said lugs being positioned so as to provide a passageway of substantially the same size as said inlet opening directly from the latter to the central portion of said head and so as to provide reduced-size passageways from said inlet opening to the opposite side portions of said body and head. 2. A sprinkler comprising an elongated, narrow, multi-apertured spray-head and a hollow body member to which said head is secured, the body member being provided with an inlet opening spaced rearwardly from the head and located approximately centrally of the length of the head, and means for effecting substantially uniform discharge of water through the openings throughout the length of said head and comprising a pair of lugs in said head at opposite sides of the path of a stream of water entering said head through said inlet opening, said lugs having inside faces substantially aligned with portions of the wall of said inlet openings, the front ends of said lugs being disposed closely adjacent said head and the rear portions of said lugs being spaced materially from the rear wall of the body member so as to provide passageways from said inlet opening to the opposite side portions of said body, said lugs being tapered laterally from said front and rear ends in substantially triangular formation, so as to provide restricted passageways at the front and rear ends thereof. 3. A sprinkler comprising an elongated, narrow, multi-apertured spray-head and a hollow body member to which said head is secured, the body member being provided with an inlet opening spaced rearwardly from the head and located approximately centrally of the length of the head, and means for effecting substantially uniform discharge of water through the openings throughout the length of said head, comprising a pair of substantially triangular lugs respectively located on opposite sides of the path of a stream of water entering said head through said inlet opening, each of said lugs being shaped to provide an inside wall disposed substantially in alignment with a portion of the wall of the inlet opening, a front wall diverging rearwardly and outwardly from said head, and a rear wall spaced from an oppositely disposed portion of the body so as to provide an elongated, restricted passageway to the adjacent end portion of the body. 4. A sprinkler comprising a substantially tubular inlet portion having an inlet opening therein, and a spray head communicating therewith, said spray head extending forwardly and laterally on opposite sides of said inlet portion to form an elongated narrow chamber, said chamber being bounded by side walls, a multi-apertured front wall, and opposite and similar rear walls diverging from said inlet opening to the extremities of said front wall, said rear walls being so arranged that said chamber tapers from a maximum depth adjacent said inlet portion to a relatively shallow minimum depth adjacent the extremities of said chamber, and a pair of baffles secured in said chamber to said side walls, said baffles having faces on opposite sides of a central passageway defined by them in prolongation of said inlet and terminating contiguous to said front wall, each of said lugs also having a face spaced from and substantially parallel to one of said rear walls so as to provide a restricted passageway therebetween, and a face joining said last mentioned face and contiguous at its other end to said front wall adjacent said central passageway. 5. A sprinkler comprising a substantially tubular inlet portion having an inlet opening therein, and a spray head communicating therewith, said spray head extending forwardly and laterally on opposite sides of said inlet portion to form an elongated narrow chamber, said chamber being bounded by side walls, a multi-apertured front wall, and opposite and similar rear walls diverging from said inlet opening to the extremities of said front wall, said rear walls being so arranged that said chamber tapers from a maximum depth adjacent said inlet portion to a relatively shallow minimum depth adjacent the extremities of said chamber, and a pair of baffles secured in said chamber to said side walls, said baffles having faces on opposite sides of a central passageway defined by them in prolongation of said inlet and terminating contiguous to said front wall, each of said lugs also having a face spaced from and substantially parallel to one of said rear walls so as to provide a restricted passageway therebetween, and a face joining said last mentioned face at a rounded vertex and contiguous at its other end to said front wall adjacent said central passageway.

HARRY E. MENG.
